[57] CLAIM

The ornamental design for a printed circuit profiler, as shown and described.

DESCRIPTION

FIG. 1 is a perspective view of the printed circuit profiler showing my new design;

FIG. 2 is a front elevational view thereof;

FIG. 3 is a side elevational view thereof with the opposite side being a mirror image;

FIG. 4 is a top plan view thereof; and,

FIG. 5 is a bottom plan view thereof.

The rear is plain and unornamented.

FIG. 1

FIG. 2
